CLAIM

The ornamental design for a tear strip packaging container, substantially as shown.

DESCRIPTION

FIG. 1 is a top perspective view of a tear strip packaging container showing my new design;

FIG. 2 is a view similar to FIG. 1 with the handle partially extended;

FIG. 3 is a view similar to FIG. 1 with the handle fully extended and locked in place and with two tear strips in a partially open position;

FIG. 4 is a bottom perspective view showing the bottom, side and end opposite to those depicted in FIG. 2.
